TRANSISTOR

Pieter Johannes Wilhelmus Jochems, Eindhoven, Netherlands, assignor, by mesne assignments, to North American Philips Company, Inc., New York, N. Y., a corporation of Delaware

Application April 19, 1954, Serial No. 424,173

Claims priority, application Netherlands May 1, 1953

12 Claims. (Cl. 317—235)

This invention relates to transistors comprising a semi-conductive member having secured to it one base and at least two other electrodes, that is to say at least one emitter and one collector. Barrier layers or rectifying junctions are provided between the member and the emitter or collector terminals, but in general, such a barrier is not provided between the member and the base. Said member is usually a monocrystal.

It is known that, when an emitter and a base are provided in an electric circuit, a variation of the current I_e in this circuit involves a variation of the current I_c in a second circuit including the base and a collector.

At a constant voltage E_c in the collector circuit, the ratio of said variations is the current amplification factor

$$\alpha = \frac{\partial I_c}{\partial I_e}$$

This factor should preferably be as large as possible.

The invention has inter alia for its object to increase the current amplification factor, particularly at high values of I_e and I_c . It is based on the recognition that under given conditions a considerable part of the current supplied by the emitter may flow to the base and does not contribute to influencing the collector current. The invention provides means for considerably reducing said loss.

Furthermore, the invention permits of reducing the so-called saturation current in the collector circuit, that is to say the collector current at an emitter current equal to zero and at a constant collector voltage.

According to the invention, the semi-conductive member comprises at least one insulating part whereof the surface at least partly adjoins an emitter or a collector. That is, a non-conductive region is interposed between the emitter or collector and the base electrode.

Consequently, such an insulating part compels the current to follow a given direction and diminishes the ineffective part of said emitter or collector.

Such an insulating part preferably consists of a cavity in the semi-conductive member, for example a bore or a sawcut.

The emitter and collector, or plural emitters and collectors, as the case may be, are preferably of the diffusion type, which may, for example, be obtained by fusing given metals onto the semi-conductive member. As a matter of fact, such emitters and collectors, which have a comparatively large surface, and which are sometimes referred to as broad area rectifying connections, frequently possess parts which do not contribute to the efficiency of the transistor.

The invention is of particular importance for transistors of comparatively high power, whose emitter and collector have a large surface and are alternately juxtaposed on the semi-conductive member.

In order that the invention may be readily carried into effect, it will now be described in greater detail with

2

reference to the accompanying drawing, which represents several examples thereof and in which

Fig. 1 is a sectional view of a transistor comprising one emitter and one collector.

Fig. 2 is a sectional view of a transistor comprising a number of such emitters and collectors.

Figures 3 and 5 are perspective views of a semi-conductive member and

Figures 4, 4a, 6 and 7 are sectional views of transistors made by means of said member.

The transistor shown in Fig. 1 comprises a semi-conductive member or body 1, for example consisting of a mono-crystal of n-type germanium, which is soldered to a base 2, which thus constitutes a base ohmic connection

15 to the body 1. This member 1 has secured to it an emitter 3 and a collector 4, both of which may consist of a quantity of indium fused onto the body. In this manner the underlying germanium is locally converted into p-type germanium at the two regions indicated by reference numeral 5, as indicated by double cross-hatching, barriers or rectifying junctions being situated at the limiting surfaces of these opposite types of germanium.

20 An insulating part or non-conductive region in the form of a cavity 6 is situated beneath the emitter 3 and thus between the latter and the adjacent p-type region 5, and the base connection 2. Thus a part 7 of the surface of the emitter 3 is made inactive with the effect that the remaining active surface influences the collector 4 to a relatively higher degree. However, a part of the contact

25 surface of the emitter 3 and the semi-conductive member 1, which part is situated at the left of the cavity 6, still provides emitter current which does not practically affect the collector.

30 Therefore it is advisable to provide insulating parts beneath an emitter situated between two collectors. Fig. 2 shows a transistor comprising two emitters 3 and three collectors 4. Beneath each emitter and each collector are provided cavities 6 so that all surface parts of the

35 emitters, which contact with the semi-conductive member, face a collector, and the current passing through the emitters (to be connected in parallel) is able to exert a comparatively strong influence on the current passing through the collectors (also to be connected in parallel). Furthermore, the active surfaces of the collectors mainly 40 face the emitters, thus avoiding as much as possible a direct current path from the collectors to the base and reducing the saturation current of the collector.

45 The shape of the insulating or non-conductive parts will partly depend upon the properties of the semi-conductive material. When this material is germanium it may, for example, be processed by sawing or drilling.

50 A number of parallel slots 8, as shown in Fig. 3, may be provided by sawing in the surface of the semi-conductive member remote from the base. The upper part of said slots is filled with longitudinal indium strips 9. Upon heating, this indium metal will fuse together with the germanium and partly diffuse into it to produce the regions of opposite conductivity type to that of the member 1 (Fig. 4). In order to prevent the indium from 55 filling the slots completely, the bottom of said slots may be covered with insulating material 14, for example SiO_2 , as shown in Fig. 4a.

60 Figures 5 to 7 show another embodiment in which openings 11 are drilled in a flat semi-conductive member 10 (Fig. 5). Said openings may either extend to the base 2, as shown in Fig. 6 or through said base as shown in Fig. 7. Into each opening a drop of indium is melted, which drops may be alternately connected as emitter and collector respectively.

65 70 If the transistor is required to be etched after melting on the emitters and the collectors, preferred constructions

comprise insulating parts in the form of cavities which extend to the outer surface of the member as shown in Fig. 7 and consequently not those shown in Fig. 6. In the first-mentioned case, the etching liquid is allowed to penetrate into the cavities.

What is claimed is:

1. A transistor comprising a semi-conductive member of one conductivity type, a base ohmic connection to said member, a pair of spaced regions in said member of the opposite conductivity type, and emitter and collector terminal connections to said regions, said member containing a non-conductive region located between at least one of said regions of the opposite conductivity type and said base connection.

2. A transistor as set forth in claim 1 wherein the non-conductive region is a cavity in said member.

3. A transistor as set forth in claim 2 wherein the cavity is a straight cylindrical aperture.

4. A transistor as set forth in claim 2 wherein the cavity is a straight elongated sawcut.

5. A transistor as set forth in claim 2 wherein a mass of insulating material at least partly fills said cavity.

6. A transistor comprising a semi-conductive member of one conductivity type, a base ohmic connection to one surface of said member, and a plurality of broad area rectifying connections to another surface of said member, said member containing at least one non-conducting portion disposed underneath one of said broad area rectifying connections and between the latter and the base connection.

7. A transistor as set forth in claim 6 wherein a non-conducting portion is present underneath each of the broad area rectifying connections.

8. A transistor comprising a semi-conductive member of one conductivity type, a base ohmic connection to one surface of said member, and at least three broad area rectifying connections to another surface of said member, said member containing at least one non-conducting portion disposed underneath one of said broad area rectifying connections and between the latter and the base connection.

4
tion, the remaining two rectifying connections being electrically interconnected and being situated on opposite sides of said one rectifying connection.

9. A transistor as set forth in claim 8, wherein the rectifying connections have an elongated form and extend approximately parallel to one another.

10. A transistor comprising a semi-conductive body having a groove of given width in one surface thereof defining a non-conducting portion in said body, emitter and collector electrodes connected in spaced relationship to said body, at least one of said electrodes being constituted by a metallic body having a width greater than said given width disposed over said groove in contact with and diffused into adjacent surfaces thereof, the bottom of said groove remaining free of conductive material, and a base electrode secured to a surface of said semi-conductive body opposite said one surface.

11. A transistor comprising a semi-conductive body having a cylindrical bore of given diameter extending through said body and defining in said body a non-conducting portion, emitter and collector electrodes connected in spaced relationship to said body, one of said electrodes being constituted by a metallic body having at least one dimension greater than said given diameter and disposed over one end of said bore in contact with and diffused into surface portions of said body surrounding said bore, the bottom of said bore remaining free of conductive material, and a base electrode secured to a surface of said semi-conductive body opposite from said one electrode.

12. A transistor as set forth in claim 11 wherein the base electrode has an opening therein aligned with said cylindrical bore.
